MEASURING FUNNEL

Winfield E. Dow, St. Petersburg, Fla.

Filed Dec. 2, 1958, Ser. No. 53,605

Term of patent 14 years

(Cl. D52—1)

Fig. 1 is a top plan view of a measuring funnel showing my new design;

Fig. 2 is a sectional view along line 2—2 of Fig. 1; and
Fig. 3 is a sectional view along line 3—3 of Fig. 1.

Fig. 4 is a side view of the funnel.
The essential features of my design reside in the portions shown by means of full lines in the drawing.

I claim:

The ornamental design for a measuring funnel, as shown and described.
